UNITED STATES PATENT OFFICE.

ABRAHAM T. H. BROWER, OF CHICAGO, ILLINOIS.

FOLDING TABLE.

SPECIFICATION forming part of Letters Patent No. 390,340, dated October 2, 1888.

Application filed February 2, 1888. Serial No. 262,829. (No model.)

To all whom it may concern:

Be it known that I, ABRAHAM T. H. BROWER, of Chicago, Illinois, have invented certain new and useful Improvements in Folding Tables, 5 of which the following is a specification.

My invention consists in a novel arrangement and construction of the spreading frames of a folding table, so that the whole will fold together neatly and compactly, and also possess 10 the requisite strength.

It further consists in the particular construction and arrangement of parts, as herein-after fully described, and particularly pointed out in the claim.

15 Figure 1 is a perspective view of a folding table embodying my invention. Fig. 2 is a detail view of the spreading frames of said table. Fig. 3 is a plan view of the same with the top shown in dotted lines. Fig. 4 is a vertical section of the same on lines *x x*, Fig. 3, with parts broken away, showing the axis.

A represents the table.

B B' represent the spreading frames.

C represents the legs.

25 D D' represent the leg-braces.

E represents the bolt which forms the axis.

F represents the casing about the bolt E for ornamenting and stiffening the same.

30 My invention consists, chiefly, in the peculiar construction and form of the spreading frames B B' and in the arrangement of the axis E, by which a single extended axis serves for both the frames B B' and the leg-braces D D'.

The frames B B' are constructed of plain 35 rectangular bars, preferably of wood, of equal width and thickness, so shaped as to exactly conform to each other when closed, lying side by side, with their outer sides parallel, as in Fig. 1. This is accomplished by the following 40 construction: The frame B is cut in a form such that if the plane in which its inner face lies be extended it will divide said frame into two equal similar portions, one lying on one side and the other on the other side of said 45 plane, and their adjacent extremities overlapping each other for a short distance. B' is then formed in the exact counterpart of B, and the edge of each is cut into at its middle overlapping portion half-way through, forming 50 a notch in each, into which, when one is inverted or reversed, the other will fit and the two will close compactly together, as above

described. In other words, both B and B' are so shaped that the outer portions of each, lying in opposite directions on either side of the 55 middle portion, where they are intended to cross, are set at a slight angle to the line of direction of said crossing portion, with the inner face of each, as they lie when closed, on either side of the middle portion lying in the 60 same plane. Then by notching each, as above described, and inverting one upon the other, the two will close compactly together, filling all interstices and the inner faces of each lying flat together, forming a regular, even, rectangular 65 figure, the thickness of which will be equal to the combined thickness of the two and the depth or width equal to that of one. It is obvious that these two bars B B' need not of necessity be of rectangular form, but may be 70 made of rounded rods, if desired, the advantage in the rectangular or square form being that in a closed position they form a more compact and symmetrical figure. The upper edges of these frames should properly be brought 75 to about the same level, in order to form a good and substantial support for the table-top when opened out, the form and outline of the lower edge being of course immaterial. The legs C are attached to the extremities of the 80 frames B B'.

The axis E passes through the middle point of the crossing portion of B B'. E is formed of a single rod or metallic bolt. This rod or bolt is extended downward, passing through 85 the middle point of the leg-braces D D', where they cross each other, and there forming an axis similar to that of the frames B B'. This rod or bolt E may be incased in a covering, F, of wood or other suitable material, to stiffen 90 and ornament it. E thus acts both as an axis for B B' and D D', and also acts as a brace and support for the leg-braces and legs, adding greatly to their strength and durability. If it is found that sufficient strength is obtained 95 without the use of the leg braces D D', it is obvious that E may be used as a single axis for B B', and not extended below the frames.

I prefer to construct my table principally of wood, cut and arranged in the form and manner described; but it is obvious that the material used is not an essential feature of my invention.

The advantage as to strength in the peculiar

form of my spreading frames B and B', it will be seen, consists in so disposing of the material of which they are constructed that they will have their greatest depth or width at their extremities, so that the legs may be firmly attached thereto, and having their greatest thickness in the middle portion, through which the axis must pass, and which would otherwise have the tendency to weaken them. Thus it will be seen that great strength is combined with great compactness.

I make no claim to the construction or arrangement of the folding top and the manner of attaching the same to the spreading frames, 15 all of which may be done in the usual and well-known ways; but

What I do claim, and desire to secure by Letters Patent, is—

In a folding table, a frame for supporting the top and carrying the legs, composed of two 20 rectangular horizontally-disposed bars of even depth and thickness, crossing each other at their middle points and notched together at said crossing portion, so as to bring the upper edge of each on about the same level, and swinging 25 on an axis through said middle portion, the outer portions of each on opposite sides of the axis being offset sufficiently to bring the inner faces of each on either side of the axis in the same plane, so that the whole will close compactly together with even top and substantially parallel sides, substantially as described.

ABRAHAM T. H. BROWER.
